UNITED STATES PATENT OFFICE.

EDWIN E. BARTLETT, OF HYDE PARK, MASSACHUSETTS.

ARBOR-PRESS.

1,234,259.

Specification of Letters Patent. Patented July 24, 1917.

Application filed April 9, 1915. Serial No. 20,296.

To all whom it may concern:

Be it known that I, EDWIN E. BARTLETT, of Hyde Park, in the county of Suffolk and State of Massachusetts, have invented certain new and useful Improvements in Arbor-Presses, of which the following is a specification.

The present invention has reference to improvements in presses and more particularly to improvements in arbor presses.

The primary object of the invention is to improve the efficiency of this class of press, as will appear from the following description.

15 The invention consists in such novel features of construction, operation and combination of parts as shall hereinafter be described and pointed out in the claims.

Referring to the drawings:

20 Figure 1 represents a rear elevation of a press embodying my invention.

Fig. 2 represents a sectional view, mostly in elevation, on the plane 2—2 of Fig. 1.

Fig. 3 represents a sectional view of a 25 detail, and is taken on the plane 3—3 of Fig. 2.

Fig. 4 represents a view similar to the upper portion of Fig. 1, but with certain parts shown in different positions from that 30 shown in the latter figure.

Fig. 5 represents a sectional view on the plane 5—5 of Fig. 4.

Fig. 6 represents a sectional view on the plane 6—6 of Fig. 1.

35 Fig. 7 represents a sectional view on plane 7—7 of Fig. 4.

Fig. 8 represents a sectional view on plane 8—8 of Fig. 7.

Like characters of reference designate corresponding parts throughout.

The frame of the press represented in the drawings is of a well known type, comprising the base 10, and the cross-bar 11 supported above said base by the posts 12, 12. 45 Extending through and guided by an aperture in the center of said cross-bar is the vertical ram or plunger 13 provided with the gear teeth 14. In mesh with the latter are the two pinions 15 and 16 formed on shafts 50 journaled in the cross-bar 11. Respectfully carried by said shafts are the gears 17 and 18 in mesh with the pinion 19. Secured to the latter is the gear 20 driven by a pinion 20^a integral with a ratchet-wheel 21 loose 55 on the pinion shaft 16. Said ratchet-wheel

is adapted to be rotated in one direction to move the plunger downwardly through the connecting mechanism, by the engagement of its spring pressed pawl 21^a actuated through the hand-lever 22 in the usual manner. The plunger may be raised by means of the hand-wheel 23 fastened to the pinion shaft 16. The foregoing described means for moving the plunger is but one of many well known forms and therefore has 60 been but briefly described and conventionally indicated in the drawings.

Secured to the rear end of the pinion shaft 15, I provide the ratchet-wheel 25. The latter is adapted to be engaged by the 70 pawls 26 and 27. Said pawls are loosely mounted on the stationary stud 29 projecting from the cross-bar 11. The independent movement of said pawls is limited by the pin 30 on the pawl 26 engaging the slot 31 in the pawl 27. Secured to the outer pawl 26 is the bar 32 on which is supported and guided the weight 33. Pivoted at one end on the latter is the rod 34 extending through an aperture in the outer end of the stud 35 projecting from the cross-bar 11. The outer 80 end of said rod is provided with the forwardly projecting handle 36.

To set the device, the rod 34 is pulled outwardly, by the handle 36, thereby sliding 85 the weight 33 to the inner end of the bar 32. This movement of the weight will tilt said bar and thus bring the pawl 26 secured thereto into engagement with the teeth of the ratchet-wheel 25. The leaf spring 39 secured to the pawl 26 and engaging the pawl 27 will cause the latter to be pressed with the pawl 26 into engagement with said ratchet-wheel. When this attachment is thus set, as power is intermittently applied 90 to the plunger through the herein described mechanism connecting it with the hand-lever 22, the pawls will successively engage the teeth of the ratchet-wheel 25 and thereby positively prevent any upward movement 100 or release of pressure of said plunger while the lever 32 is being raised. This holding of the pressure is the essence of the present invention. Heretofore, the only means that has been employed for holding the pressure, while the lever 22 is being raised, is to grip the hand-wheel 23, which, when a great 105 amount of pressure is being applied requires an extra man to operate, and even then, because of the necessary torsional weakness of 110

the shafts of the mechanism connecting the hand-wheel to the plunger, the pressure is not sufficiently held. It is to be noted that my device operates directly on the pinion which meshes with the rack on the plunger, so that the pressure is positively held.

The pressure of the pawls 26 and 27 on the ratchet-wheel 25 may be varied, as desired, by varying the distance said weight is moved from the center of the bar 32, which would be of particular importance if a friction disk and a suitable pawl were used in place of the ratchet-wheel and pawls shown.

The pawl 27 is longer than the pawl 26 by one-half the distance between the teeth of the ratchet-wheel, which has the effect of, but is much stronger than, a ratchet-wheel having twice the number of teeth and only one pawl.

20 The pawls 26 and 27 may be readily thrown out of engagement with their ratchet-wheel by sliding the weight 33 to the outer end of the bar 32. The pin 40 secured to the stud 29 limits the latter movement of the pawls. (Figs. 2, 3 and 4.)

While it is preferred to employ the specific construction and arrangement of parts shown and described, it will be understood that this construction and arrangement is 30 not essential except so far as specified in the claims and may be changed or modified within the scope of the claims without departing from the broader features of the invention.

35 Having thus described my invention, I claim as new and desire to secure by Letters Patent:

1. In a press of the character described, the combination, of a work supporting member, a plunger in lateral alinement therewith, mechanism for operating said plunger to apply pressure to work placed on said supporting member, with means separate from said plunger operating mechanism for positively holding the said pressure while said plunger operating mechanism is at rest.

2. In a press of the character described, the combination, of a work supporting member, a plunger in lateral alinement therewith, means for reciprocating said plunger, said means including a pinion in mesh with a rack on said plunger, means for rotating said pinion with means adapted to be moved into engagement with a member carried by 55 said pinion for preventing rotation thereof in one direction but allowing rotation thereof in the opposite direction.

3. In a press of the character described, the combination, of a work supporting member, a plunger in lateral alinement therewith, means for reciprocating said plunger, said means including a pinion in mesh with a rack on said plunger, means for rotating said pinion, a ratchet-wheel carried by said 65 pinion, a pawl, with means for moving said

pawl into engagement with said ratchet-wheel to prevent rotation thereof in one direction, said latter means separate from said means for rotating said pinion.

4. A press of the character described, having, in combination, a work supporting member, a plunger in lateral alinement therewith, means for reciprocating said plunger, said means including a pinion in mesh with a rack on said plunger, means for 70 rotating said pinion, a ratchet wheel carried by said pinion, a pawl in engagement with said ratchet wheel to prevent rotation thereof in one direction, a substantially horizontal bar secured to said pawl and a weight 75 adapted to be moved on said bar to move said pawl out of engagement with said ratchet wheel, said pawl not a part of said means for rotating said pinion.

5. A press of the character described, having, in combination, a work supporting member, a plunger in lateral alinement therewith, means including a pinion for reciprocating said plunger, a pawl engaging member carried by said pinion, a pawl in 90 engagement with said pawl engaging member to prevent rotation thereof in one direction, with means for varying the pressure of said pawl on said pawl engaging member, said pawl not a part of said means for 95 reciprocating said plunger.

6. A press of the character described, having, in combination, a work supporting member, a plunger in lateral alinement therewith, means including a rotatable shaft 100 for reciprocating said plunger, a ratchet-wheel secured to said shaft, a stationary stud, a pawl pivoted on said stud and held in engagement with said ratchet-wheel by gravity, a second pawl pivoted on said stud 105 and held in engagement with said ratchet-wheel by a spring secured to the former pawl, said pawls being of different lengths, all substantially for the purpose described.

7. A press of the character described, having, in combination, a work supporting member, a plunger in lateral alinement therewith, means including a rotatable shaft for reciprocating said plunger, a ratchet-wheel secured to said shaft, a pawl sustained 115 in engagement with said ratchet-wheel by gravity, a second pawl of a different length sustained in engagement with said ratchet-wheel by a spring, with means for disengaging said pawls from said ratchet-wheel.

8. A press of the character described, having, in combination, a work supporting member, a plunger in lateral alinement therewith, means including a rotatable shaft for reciprocating said plunger, a pawl engaging member secured to the rear end of said shaft, a pawl pivoted on a stud, with means for swinging said pawl in and out of engagement with said pawl engaging member, said means including a rod having its 125 130

outer end extending toward the front of the machine, said pawl not a part of said means for reciprocating said plunger.

9. An attachment of the character described adapted to be applied to an arbor press, comprising a ratchet-wheel adapted to be secured to a pinion shaft in mesh with a rack on the plunger of said press, a pawl pivoted on a stud adapted to be secured to the frame of said press, a substantially horizontal bar secured at its center to said pawl, a sliding weight on said bar, with means
- 5
- 10

adapted to be supported by the frame of said press for sliding said weight on said bar to swing said pawl in and out of engagement with said ratchet-wheel for the purpose set forth. 15

In testimony whereof I have affixed my signature in presence of two witnesses.

EDWIN E. BARTLETT.
